UNITED STATES PATENT OFFICE.

WILLIAM ROUNDS, OF CHESTER, VERMONT.

CRAYON AND ERASER HOLDER.

SPECIFICATION forming part of Letters Patent No. 269,468, dated December 19, 1882.

Application filed March 28, 1882. (Model.)

To all whom it may concern:

Be it known that I, WILLIAM ROUNDS, of Chester, in the county of Windsor and State of Vermont, have invented certain Improvements in a Chalk, Crayon, and Eraser Holder Combined, of which the following is a specification.

The object of my invention is to provide an inexpensive crayon and eraser holder combined which may be used to advantage in all kinds of blackboard work; and it consists in constructing from one strip of thin elastic metal, of suitable length and width, the body or main part of crayon-holder, and in such a way as at the same time to form at one end thereof a loop which serves as a clamp to receive and hold the eraser, which may be made of cotton, cotton or wool flannel, or other suitable material, and inserted therein preparatory to adjusting the holder for the reception of the crayon.

My combined holder is composed of two pieces—to wit, the body or main part thereof and a metallic ring or band—as shown by the accompanying drawings, which are made a part of this specification, and in which—

Figure 1 is a view of my improved holder with its clamping-band removed and in readiness to receive the eraser. Fig. 2 is a view of the same with the eraser inserted, and represents the holder in readiness to receive the crayon; and Fig. 3 is a view of the holder with the eraser and crayon inserted ready for use.

The holder may be made of any suitable material, preferably of thin elastic metal, such as tin. The body is preferably made from a single piece of material, cut in proper form, shaped and bent, as shown, to form the arms or jaws A A and the curved portion B, which unites the jaws and forms a clamp or holder for the eraser D. The jaws are concaved and slightly corrugated at the open end, to adapt them to the shape of crayon, and both the jaws and

the eraser-holding clamp are closed and secured by the clamping-band C.

D is the eraser, made of cotton, cotton or 45 woolen flannel, or any other suitable material, and inserted in the clamp B, as shown.

E is the crayon, inserted between the spring-jaws A A, in which position it is adjustably secured by the clamping-band C, the adjustment 50 of the crayon being readily effected by moving band C toward the eraser until the jaws A A open enough to release the crayon, which is then projected to expose the desired length, or retracted to entirely cover the crayon, and the 55 jaws secured by returning the clamping-band.

I do not limit myself to the construction of the body of the holder of metal or in a single piece, as it may be made in several pieces, and from any suitable material; nor do I limit myself to the use of a metallic clamping-band.

Having thus described my invention, what I claim as new, and desire to secure by Letters Patent, is—

1. A combined crayon and eraser holder, 65 consisting of crayon-holding arms or jaws and a clamp for holding the eraser, said jaws and clamp being closed by a single clamping-band.

2. A combined crayon and eraser holder, consisting of crayon-holding jaws united by a 70 curved portion, forming a clamp or holder for the eraser, and a clamping-band that secures both the crayon and eraser holders, substantially as set forth.

3. In a combined crayon and eraser holder, 75 the concaved spring-jaws A A; curved portion B, uniting said jaws and forming a clamp or holder for the eraser D, and the clamping-band C, substantially as described and shown.

WILLIAM ROUNDS.
